Samuel H. Titus

United States Patent Office.

SAMUEL H. TITUS, OF PENNINGTON, NEW JERSEY.

Letters Patent No. 65,305, dated May 28, 1867.

IMPROVED CLOTHES-DRYER.

The Schedule referred to in these Letters Patent and making part of the same.

TO ALL WHOM IT MAY CONCERN:

Be it known that I, SAMUEL H. TITUS, of Pennington, in the county of Mercer, and State of New Jersey, have invented a new and improved Clothes-Horse, for the drying of clothes thereon; and I do hereby declare that the following is a full, clear, and exact description of the construction and operation of the same, reference being had to the annexed drawing, making a part of this specification.

Figure 1 represents a perspective view of the clothes-horse when the frame is spread out for drying thereon. A B and C D represent the pair of cross-standards, whereon the other parts of the frame are constructed. Nearly all the parts of the frame being duplicated, the same letters of reference are intended to designate similar parts thereof. E F and G H, as also E I and F H, represent the short parallel spreading arms of the frame; K K K are the clothes-bars, whereon the clothes are to be hung to dry; L L is the roller-belt bar, and M M the belts for winding up and regulating the extension of the cross-standards; N is a ratchet-wheel, firmly fastened on to the exterior end of the roller-belt bar, and to which is applied the spring-catch or pawl P; O represents a lever or thumb-head firmly fastened on to the exterior end of the roller-bar L L, whereby it is turned. In the construction of the frame, the extreme ends of the clothes-bars K K K are reduced in diameter with a shoulder thereon, so as to pass through the cross-standards and parallel arms. In all cases where these reduced ends of the clothes-bars pass through the standards and parallel arms, or through two of the said parallel arms, the exterior ends of the clothes-bars are firmly fastened by glue, pins, or otherwise, to said standards or arms, whereas the other portions of said reduced ends pass loosely through the standards or parallel arms, so as to allow of motion thereon. The bar R R, whose ends pass through the two pair of standards A B, C D, forms the centre of motion, whereon the standards move in extending or spreading out the frame, or when contracting and closing up the same for removal or otherwise.

The operation required in the use of this improved clothes-horse is very simple and obvious. By pressing on the extreme end of the spring-catch or pawl P, the catch is released from the ratchet-wheel N, so that the standards may then be spread out or extended to the full extent of the belts. By this operation the upper clothes-bars are brought down near to the ground, and at a convenient height to hang the clothes thereon. When these upper bars are filled, a few turns of the lever or thumb-head O will wind up the belts, draw the standards together, and raise the frame and upper already loaded clothes-bars to a more elevated position, so that the underneath or remaining bars may now be filled as aforesaid.

I do not claim, broadly, any of the separate and particular parts embraced in the construction of the above-described frame or clothes-horse; but what I do claim as my invention, and desire to secure by Letters Patent, is—

The combination and construction of a clothes-horse, having the cross-standards A B and C D, parallel arms E F G H E I and F H, roller L L, and belt M M, ratchet N, spring-catch P, and thumb-head O, with the clothes-bars K K K, substantially as above described, and for the purposes herein set forth.

SAMUEL H. TITUS.
